UNITED STATES PATENT OFFICE.

LEO ALBERT KRUPP, OF CAREY, OHIO, ASSIGNOR OF ONE-HALF TO PEAT INDUSTRIES, LIMITED, OF MONTREAL, CANADA, A CORPORATION OF CANADA.

EXCAVATING-MACHINE.

1,043,113.

Specification of Letters Patent.

Patented Nov. 5, 1912.

Application filed April 14, 1911. Serial No. 621,125.

To all whom it may concern:

Be it known that I, LEO A. KRUPP, a citizen of the United States, residing at Carey, county of Wyandot, State of Ohio, have invented a certain new and useful Improvement in Excavating-Machines, and declare the following to be a full, clear, and exact description of the same, such as will enable others skilled in the art to which it pertains to make and use the same, reference being had to the accompanying drawings, which form a part of this specification.

My invention has for its object to produce a simple and novel apparatus for easily and economically excavating peat or the like.

In carrying out my invention I make use of an endless chain of excavator buckets of peculiar construction and therefore, viewed in one of its aspects, my invention may be regarded as consisting in improvements in excavator buckets.

Peat in its natural state is wet and sticky and is apt to adhere to the buckets so as to prevent the buckets from being fully emptied when they reach the discharge point. In accordance with my invention I provide means for automatically clearing the buckets of their contents when the discharge point is reached and therefore my invention, viewed in a further aspect, may be regarded as relating to improved discharging means for excavator buckets.

I support the endless chain of buckets in such a manner that the entire chain may be swung through a considerable angle about a vertical axis, thus permitting a path much wider than a single bucket to be excavated without changing the lateral position of the carriage; and therefore my invention, viewed in a further aspect, may be regarded as comprising an improved apparatus adapted to cut a path of great width.

The various features of novelty whereby my invention is characterized will herein-after be pointed out with particularity in the claims; but, for a full understanding of my invention and of its object and advantages, reference may be had to the following detailed description taken in connection with the accompanying drawings, wherin:

Figure 1 is a side elevation of the rear

portion of an excavating machine arranged in accordance with my invention; Fig. 2 is a plan view of the parts shown in Fig. 1, one position of the main boom being shown in full lines and another position in dotted lines; Fig. 3 is a plan view on a larger scale of the pivoted end of the boom and a portion of the chain of excavator buckets; Fig. 4 is a side view of the parts shown in Fig. 3; Fig. 5 is a section on an enlarged scale on line 5—5 of Fig. 4; and Fig. 6 is a perspective view of one of the buckets.

Referring to the drawings, 1 represents a movable carriage of any suitable construction. At the rear thereof is a suitable crane 2 pivoted so as to swing about a vertical axis. In the arrangement shown, (see Fig. 2) the crane is provided with suitable outriggers 3 to the extremities of which are connected blocks and tackles 4 actuated by drums 5 revolvably mounted upon the carriage.

6 is a power shaft adapted to be connected to either of the drums through clutches 7.

Upon the crane is mounted a boom 8 adapted to swing about a horizontal axis. The boom is adapted to carry the excavating buckets and it may be raised and lowered to adjust the depth to which a cut will be made. In the arrangement shown there is a bail 9 secured to the boom near the outer end, and a cable 10, passing over pulleys 11 and 12 mounted respectively on the bail and at the upper end of the crane, serves to raise and lower the boom. The cable 10 may be actuated in any suitable way as, for example, by means of a drum 13 to which its inner end is connected.

All of the parts heretofore described may take any usual or preferred forms since the only feature of my invention thus far described consists in a boom which may be swung in a vertical plane and also about a vertical axis.

The pivotal support for the boom on the crane may conveniently take the form of a shaft 14 passing through the inner end of the boom and revolvably supported in bearings 15 on the crane. By allowing the shaft 14 to run freely in the boom, it may also be made to serve as the driving member for the chain of buckets and the automatic cleaner

to be hereinafter described. To this end the shaft 14 is provided with two sprocket wheels 16 spaced apart somewhat less than the width of the boom. At the free end of the boom are similar and similarly spaced sprocket wheels 17, thus making provision for driving two endless chain members which extend longitudinally about the boom.

- 10 In accordance with my invention I make use of excavator buckets of peculiar construction. The construction of the buckets is perhaps most clearly illustrated in Fig. 6. Each bucket consists of two sheet metal 15 sides 18 and a back 19, thus leaving the bucket open at the top, at the bottom and at the front. The two side members of the bucket are tied together by means of a U-shaped cutting member 20, the arms of 20 which are riveted or otherwise secured to the side members of the bucket. Consequently, as the bucket is drawn into the material to be excavated, it presents a cutting edge along the bottom and at both sides. 25 Within the upper end of each bucket are two narrow bars 21, each spaced apart a short distance from one of the side walls and lying parallel therewith. The endless chain is formed by connecting the buckets 30 together with chain sections 22, each chain section having one end fastened between one of the bars 21 and the adjacent side of one bucket and its other end between the corresponding bar and the adjacent side of the 35 next bucket. In this way I produce an endless chain of buckets which consists of two separated sprocket chains on which the buckets are hung, the sides of the buckets forming parts of the sprocket chains. The 40 bars 21 are spaced apart from the sides of the buckets far enough to permit the sprocket wheels 16 and 17 to enter the space between the bars and the sides of the buckets, the parts being so proportioned that the 45 actual driving is effected through the chain sections 22.

Along the upper side of the boom are two parallel tracks 23 conveniently made of angle irons each of which has one flange extending horizontally and the other flange extending vertically. On the underside of the boom are two double tracks 24, these being conveniently made of channel irons. The endless chain of buckets is supported 50 on the tracks by means of shoes 25 which project laterally from the sides of the buckets at the tops thereof. These shoes may conveniently consist of blocks of wood shaped to fit into the channel-iron tracks on 55 the underside of the boom, the shoes on that portion of the chain which lies above the boom simply resting upon the tracks 23. It will thus be seen that the buckets are firmly supported while they remain on the under-

65 side of the boom and must follow a given path when the driving power is applied. Since the shoes project out beyond the sides of the buckets, some provision must be made for affording a clearance for the shoes during the excavating processes. This may 70 conveniently be done by providing the buckets with auxiliary cutting blades 26 which are secured to the sides at the front ends of the buckets and project forwardly and outwardly, the flare of the auxiliary cutting 75 blades being sufficient to carry them out beyond the planes of the shoes.

The buckets are intended to excavate and become filled while they travel on the underside of the boom and therefore some means 80 must be provided for preventing the contents from dropping through the open bottoms as soon as the buckets rise above the level of the material in which the excavation is taking place. To this end I provide a 85 stationary shield 27 on the underside of the boom, this shield being spaced far enough apart from the boom to lie close to the bottoms of the buckets as they pass along the boom and prevent the contents of the buckets from dropping out before the discharge 90 point is reached. The shield may take the form of a flat metal plate or a shallow channel and is suspended from suitable hangers 95 28 extending downwardly from the boom. The point at which the shield must become operative varies with the depth to which the cut is being made and therefore I prefer to provide the shield with an extensible section 100 29 (see Figs. 4 and 5) the member 29 overlapping the outer end of the main portion of the shield and being adjustably connected thereto so that it may be slid in and out to vary the effective length of the shield. In the arrangement shown the extensible section 105 is held in place by means of one or more bolts 30 extending down from the member 29 through a slot 31 in the fixed portion of the shield. It will of course be understood, however, that other fastening 110 means may be employed. The shield terminates just before the inner end of the boom is reached and at this point the contents of the buckets are discharged. In the arrangement shown, there is a conveyor 32 115 which extends into proximity to the inner end of the shield for the purpose of receiving the excavated material from the buckets. It will of course be understood, however, that the contents of the buckets may be disposed of in any suitable manner.

As I have heretofore stated, peat is wet and sticky and some of the contents of the buckets will remain in the buckets if gravity alone is relied upon for effecting the discharge when the discharge point is reached. In order to make the discharge of the contents of the buckets certain and positive I

have provided a power driven ejector which takes the form of a double-ended paddle 33 secured to the shaft 14 between the sprocket wheels 16. The parts are so proportioned and adjusted that as each bucket approaches the sprocket wheel 16, one of the paddles descends into the top of the bucket and, as the bucket travels around the sprocket wheels the paddle passes into and through the bucket, pushing the contents positively through the bottom. In Fig. 3 one of the buckets is shown as having almost completed its travel around the sprocket wheels and one of the paddles now projects entirely through the bucket. The succeeding bucket is just coming into engagement with the sprocket wheels and the other paddle is just about to descend into this bucket. It will thus be seen that as the buckets travel around the sprocket wheels the paddles sweep clear through the same and insure a complete discharge of their contents.

The shaft 14 may be driven in any suitable manner. In the arrangement shown, the shaft is provided at one end with a gear wheel 34 which meshes with a pinion 35 carried by a counter shaft mounted on the crane. The counter-shaft is geared to a second counter-shaft 36 mounted upon the crane near the base thereof, the gearing between the two counter-shafts conveniently taking the form of a sprocket chain 37. At the pivotal axis of the crane is a horizontal bevel gear 38 which meshes with a pinion 39 on the shaft 36. The gear 38 may be driven by a driving gear 40 mounted upon the end of a suitable shaft 41. The shaft 41 may be mounted in stationary bearings on the carriage without interfering with the driving connection between the members 38 and 40 when the crane is swung about its axis.

The operation of my apparatus will now be understood. The excavating devices are arranged in rear of the carriage so that the carriage is not required to run over areas from which material has just been excavated. Consequently the width of the path which is cut does not depend upon the width of the carriage and is limited only by the length and the sweep which it is practicable to give to the boom. To begin an excavation: the apparatus is moved to the starting point; the boom is swung laterally to one boundary of the ditch or path to be excavated; the chain of buckets is set in operation; and the boom is lowered until the buckets cut to a depth of about a foot. The crane is then set in motion, slowly sweeping the boom across the path to be cut until the opposite side is reached. When an initial cut has been completed, the boom is again lowered and is started back toward the opposite side. In this way the boom is swung back and forth, being lowered at each limit

of its movement, until the excavation has 65 proceeded to the desired depth as indicated in Fig. 1. Thereafter no change is made in the vertical position of the boom, it being simply swung back and forth in the transverse direction; the apparatus being moved 70 forward the proper distance for a new cut at the end of each swinging movement of the boom. It will be seen that after the buckets leave the face of the inclined bank 42 they pass above the shield and their contents are prevented from dropping out through the open bottoms. When a bucket reaches the upper end of the shield, one of the automatic cleaning paddles enters the same and its contents are discharged upon 80 the conveyer 32 which carries the excavated material to any desired point.

It will thus be seen that I have produced a simple and novel apparatus for excavating peat, or other material which is not too 85 hard, rapidly and economically, making it possible to excavate to any desired depth and across a path of considerable width while the apparatus travels straight ahead.

While I have illustrated and described 90 only a single embodiment of my invention in which all of the various novel features are combined, and have referred to it generally as a peat excavator, I do not desire to limit myself to the specific structural details thus illustrated and described, or to an apparatus which necessarily contains every 95 novel feature, or to an apparatus adapted solely for excavating peat, but intend to cover all constructions and arrangements 100 which fall within the terms employed in the definitions of my invention constituting the appended claims.

I claim:

1. In an excavating machine, an endless 105 chain of buckets open at the top and at the bottom, an adjustable support for said buckets, a shield lying below the lower member of said chain to close the bottoms of the buckets during their travel across the 110 shield, a rotary paddle arranged at one end of the shield and adapted to enter the buckets and swing entirely through them from the top through the bottom when they reach that end of the shield and positively 115 discharge their contents, and means for actuating said chain and said paddle so as to bring the paddle into operative relation to each of the buckets as it reaches the afore- 120 said end of the shield.

2. In an excavating machine, a swinging boom, an endless chain of buckets extending longitudinally of the boom and passing around the free end thereof, two sprocket wheels at each end of the boom, each set of 125 sprocket wheels being spaced apart a distance slightly less than the width of the buckets, said chain of buckets consisting of

bucket members' each having secured upon the inside thereof two longitudinal bars separated far enough from the sides to permit the passage of the sprocket wheels together with sprocket chain sections connected at their ends between said bars and the sides of the buckets.

In testimony whereof, I sign this specification in the presence of two witnesses:

LEO ALBERT KRUPP.
